UNITED STATES PATENT OFFICE.

HENRY A. SCHAEFER, OF ROCHESTER, NEW YORK, ASSIGNOR TO SCHAEFER & SCHLEGEL, OF SAME PLACE.

DESIGN FOR TRIMMING.

SPECIFICATION forming part of Design No. 32,242, dated February 13, 1900.

Application filed January 2, 1900. Serial No. 175. Term of patent 7 years.

To all whom it may concern:

Be it known that I, HENRY A. SCHAEFER, a citizen of the United States, residing in the city of Rochester, county of Monroe, and State of New York, have invented and produced a new, useful, and original Design for Trimming, of which the following is a specification, reference being had to the accompanying drawing, forming a part thereof.

My design consists of a fringe A, depending from the lower side of the fancy heading B, composed of the upper broad edging C and the lower strip D, and between the two latter is a narrower strip E, and provided upon either side of the latter, between the prox-

mate edges of strips C and D, is the open-work F and G. The "open-work," so called, represents the general appearance of interlocking cord or thread loops *a* and *b*, the former extending from the outside edging or heading and the latter from the strip E.

Having described my design, what I claim as new, and desire to secure by Letters Patent, is—

The design for a trimming, substantially as herein shown and described.

HENRY A. SCHAEFER.
